J. Knight,

Truss.

Patented Dec. 14, 1830.

James Knight, of Baltimore, Maryland
Letter of Patent.

The schedule referred to in these Letters Patent, and making part of the same, containing description in the words of the said James Knight himself, of his improvement in Tuesy.

To all to whom these presents shall come:

Be it known that I, James Knight, of the city of Baltimore, in the County of Baltimore and State of Maryland have invented and useful improvement in Tuesy, and that the following is a full and exact description of the construction and operation of the said machine as invented or improved by me.

I shall first give a description of James G. Hall's Patent hinge and pivot, in order to point out clearly the nature of my improvement. The construction is as follows; Two concave pads are attached to an elastic steel spring by means of a hinge and pivot; this spring passes from one pad over the other and around to the spine where one of the pads is placed and the other in the region over the rupture. This tissue is attended with many disadvantages and inconveniences among which is the pressure on the spine in young people; this pressure which must necessarily be considerable in order to keep the instrument in its place, bears on certain points of the spine and on the rupture, and is frequently on its first application so painful as to be insupportable for more than a few hours at a time when the rupture is bad. The hinge and pivot in the center allow the pad to have motion in any direction and in certain attitudes of the body the irritation may be increased and great pain produced. In order to overcome this inconvenience he applies two of his springs one on the other and over them the object cannot change be accomplished. I have endeavored to overcome these difficulties and shall now give a description of

my trap; the pad is encircling upon the back; the pad over the nupture is concave so as to correspond with the slight concavity of the abdomen and is sustained over the nupture by means of a small steel spring which is also moved to fit the concavity of the abdomen and is riveted fast to the metallic plate in the back of the pad; the other end of this spring is attached to an elastic steel mainspring by means of a pivot with a long head which allows a lateral motion to the small spring. The main spring is covered with leather and buckles around the hip when it is fixed. In applying this trap the spring must be brought around the body in the same manner as in the application of A. G. Mulls traps, the small spring will form an angle with the main spring and the pad will be in perfect coaptation with the hernial parietes as the end of the main spring which is above the hip extends a small distance from the abdomen, when the trap is buckled perfectly tight the pad will press sufficiently to keep up the intestine in the most difficult cases of hernia without producing pain, and the pressure is by this means rendered equal around the body; this circumstance is of great importance in the treatment of hernia in labouring people and in infants as the trap can be kept on without pain whilst they are in the recumbent position. A. G. Mulls trap on the contrary cannot be worn whilst the patient is lying down in consequence of the pain caused by the pressure of the back pad on the spine, for my trap the pad is kept in perfect coaptation with the hernial parietes under every possible inflection or attitude of the body by the elasticity of a steel spring and not by a hinge and pivot as in A. G. Mulls trap. This latter arrangement allowing of too much motion whilst the elastic spring having a permanent extension yields to all motions required but always maintains an equal pressure. What I claim as my invention and improvement in a trap which is made to press equally around the body by means of an additional spring and fixed concave pad; the pressure being

being graduated by means of a strap and buckle, which
the strap is permanently fastened around the body, making it
different in principle from all other braces; my strap can be
worn, sitting, lying or standing with so little inconvenience
as to be worn by the youngest infant.
